Primary Examiner — Clare E Heflin(57) **CLAIM**

The ornamental design for an LED lantern, as shown and described.

DESCRIPTION

FIG. 1 is a front elevational view of an LED lantern showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a first perspective view thereof; and,

FIG. 8 is a second perspective view thereof.

The broken lines shown on the drawings depict portions of the LED lantern that form no part of the claimed design.
